UNITED STATES PATENT OFFICE

144,527

DESIGN FOR A BUS MARKER LIGHT

Wagn Trautner, Onondaga County, N. Y.

Application September 6, 1945, Serial No. 121,873

Term of patent 14 years

(Cl. D48—32)

To all whom it may concern:

Be it known that I, Wagn Trautner, a citizen of the United States, residing in the county of Onondaga and State of New York, have invented a new, original, and ornamental Design for a Bus Marker Light, of which the following is a specification, reference being had to the accompanying drawing, forming a part thereof.

Figure 1 is a perspective view of a bus marker light showing my new design.

Figure 2 is a front elevational view.

Figure 3 is a side elevational view thereof.

I claim:

The ornamental design for a bus marker light, substantially as shown.

WAGN TRAUTNER.
